(57) **CLAIM**

I claim the ornamental design for culinary tool, as shown and described.

DESCRIPTION

FIG. 1 is a front, top perspective view of the culinary tool embodying the new design;

FIG. 2 is a front view thereof, the rear view being a mirror image thereof;

FIG. 3 is a right side view thereof, the left side view being a mirror image thereof;

FIG. 4 is a top view thereof; and,

FIG. 5 is a bottom view thereof.

FIGS. 1-5 show features of a culinary tool in phantom lines. These features are shown for environmental purposes and do not form any part of the claimed design. Further, the phantom lines immediately adjacent the solid-line portions of the design form the boundary of the design, with the phantom lines forming no part of the claimed design.
